United States Patent Office.

JAMES B. WILLIAMS, OF GLASTENBURY, ASSIGNOR TO THE HARTFORD SORGHUM MACHINE COMPANY, OF HARTFORD CONNECTICUT.

Letters Patent No. 91,889, dated June 29, 1869.

IMPROVED METAL-CORRUGATING MACHINE.

The Schedule referred to in these Letters Patent and making part of the same.

To all whom it may concern :

Be it known that I, JAMES B. WILLIAMS, of Glastenbury, county of Hartford, and State of Connecticut, have invented certain new and useful Improvements in Metal-Corrugating Machine; and to enable others skilled in the art to make and use the same, I will proceed to describe its construction and operation, reference being had to the drawings, in which the same letters indicate like parts in each of the figures.

In the accompanying drawings—

Figure 1 is a side elevation.

Figure 2 is an inside end view.

Figure 3 is an explanatory view of the head of the machine.

a are the legs which support the machine.

b are guide-ways.

c is a table or bed, upon which the metal sheets are placed to be acted upon by the machine-mechanism.

d is a bar arranged between the guide-ways *b*, so as to be elevated by the joint action of the levers *e* through the arms *f*.

g are circular depressions or grooves, formed in the heads *h*.

i are compressing-bars, having circular guides *j*, formed or secured upon the ends of said bars, the object of which is to firmly hinge the ends of the bars *i* in the grooves *g*.

The edges *k*, of these bars, are made of such shape as to fit closely up to the side of, and near the upper edge of bar *d*.

The sheet of metal is first inserted or placed upon the bed-plate *c*, over the bar *d*, while the oscillating

bars *i* are in an elevated position; then the crimping-bar *d*, is lifted against the under side of the metal sheet, by means of the levers *e*, which are held in an elevated position by means of the notched arms *m*; then the bars *i* are turned down by the levers *n* on to the bed-plate, and firmly against the metal, thus forming an elevation the shape of the upper portion of the bar *d*, and firmly compressed thereto; then the oscillating bars are elevated into their resting position, and the crimping-bar *d* is dropped to its level with the bed, and is then ready for a new operation.

Thus I am enabled to form one corrugation after another, in quick succession, and at any desired point or angle upon the sheet, thus reducing the mechanism of a corrugating-machine to a state of great simplicity, and enabling the operator to produce perfect work in a short amount of time.

I believe I have thus shown the nature, construction, and advantage of this invention, so as to enable others skilled in the art to make and use the same therefrom.

What I claim, and desire to secure by Letters Patent, is—

The crimping-bar *d*, arranged between the guide-ways *b*, in combination with the oscillating compressing-bars *i*, arranged and operating substantially as described.

JAMES B. WILLIAMS. [L. S.]
